(57) **CLAIM**

The ornamental design for a folding game with backboard, as shown and described.

DESCRIPTION

FIG. 1 is a top perspective view of a folding game with backboard in an unfolded state showing the new design with goal cups placed in openings;

FIG. 2 is a top perspective view of the folding game with backboard in an unfolded state;

FIG. 3 is a left side view of the folding game with backboard in an unfolded state;

FIG. 4 is a right side of the folding game with backboard in an unfolded state;

FIG. 5 is a back view folding game with backboard in an unfolded state;

FIG. 6 is a front view of the folding game with backboard in an unfolded state;

FIG. 7 is a top view of the folding game with backboard in an unfolded state;

FIG. 8 is a bottom view of the folding game with backboard in an unfolded state; and,

FIG. 9 is a top perspective view of the folding game with backboard in a folded state.

The broken lines in the drawing figures of the folding game with backboard such as those that show fastening hardware or goal cups form no part of the claim.

1 Claim, 9 Drawing Sheets
